UNITED STATES PATENT OFFICE.

THOMAS B. RULE, OF ARKLOW, IRELAND.

SUPPORTING MECHANISM.

1,261,856.

Specification of Letters Patent. Patented Apr. 9, 1918.

Application filed August 17, 1916. Serial No. 115,427.

To all whom it may concern:

Be it known that I, THOMAS B. RULE, a subject of the King of Great Britain, residing at Arklow, Ireland, have invented certain new and useful Improvements in Supporting Mechanism, of which the following is a specification.

My invention relates to adjustable supporting mechanism.

10 One object of the invention is to provide an improved type of mechanism of this nature which may for instance be used to support an electric lamp or fixture and which will remain in adjusted position through frictional engagement of elements employed and which elements are mounted and constructed so as to be unaffected by the movement or adjustment of the article supported.

15 In addition, I aim to provide an outlet member having an outlet means for an electric wire and a pivot with a conical wall, an outlet member into which the pivot extends, a sleeve to engage the pivot member, means on the outlet member to prevent turning of 20 the sleeve relatively to the pivot and means coöperating with the outlet member to vary the degree of frictional contact between the pivot and the sleeve.

With the above and additional objects, 25 such as will hereinafter appear, in view, the invention has been embodied in one preferred form, due regards being given to the efficiency and durability of the parts and their cost of manufacture, as illustrated in 30 the accompanying drawings wherein;—

Figure 1 is a view in side elevation illustrating the improvements applied to an electric lamp or fixture;

Fig. 2 is a view mostly in vertical section, 40 on an enlarged scale, through the improved joint employed;

Fig. 3 is a cross sectional view on the line 3—3 of Fig. 2;

Fig. 4 is a fragmentary longitudinal sectional view through a second form of joint which may be employed;

Fig. 5 is a cross sectional view on the line 5—5 of Fig. 4;

Fig. 6 is a detail view partly in plan and partly in section showing the connection 50 of the pivot member to its support, and

Fig. 7 is a cross sectional view on the line 7—7 of Fig. 4.

Referring specifically to the drawings, wherein like reference characters designate 55 like or similar parts, my improvements may be used in connection with any preferred article to be supported but has particularly been devised for use in connection with an electric lamp. Let 7 represent any suitable 60 form of outlet member, which may be attached to any suitable support, for instance a wall, ceiling, or standard, and which is hollow and is as well provided with an outlet opening 8 so that electric wires 9 may 65 pass therethrough. The supporting arm may be generally designated 10 and the lamp or other article supported thereby be generally designated 11. By means of a swivel head 12 and other details of construction 70 to be described, the arm 10 is supported from the member 7 to swing therefrom in any suitable plane according to the position of the part and for instance in a horizontal plane as suggested by Fig. 1 of the drawings. At 75 the same time the arm 10 is composed of a plurality of sections 13 and 14 pivoted together at 15 for movement in a plane at right angles to the general path of movement of the arm.

80 Outlet 7 includes a bracket 16 through which the opening 8 is specifically provided and which is also provided with a sleeve 17 through which a pivot member 18 passes and is fastened thereto by soldering or by means 85 of a set screw 19. Member 18 has pivot portions 20 one extending on each of opposite sides beyond the sleeve 17. Slidably mounted on each pivot portion 20 is a retarder block 21 having an opening corresponding 90 to the shape of the pivot portion and at the opening adapted to frictionally engage the pivot portion. The block has a longitudinal groove 22 into which a pin 23 may extend to prevent turning of the friction sleeves or 95 blocks relatively to the pivot portion. These

pins 23 are preferably mounted by means of screw threads at 24 from the head 12. Blocks 21 are reduced so as to provide shoulders at 25 to be engaged and held in place by gland extensions 26 of adjusting nuts 27. The gland extensions have screw threaded engagement at 28 with the inner walls of tubular extensions 29 of the head 12. The nuts 27 also preferably have externally 10 knurled or roughened rings of greater diameter than the diameter of the portions 29 and connected to the gland extension 26 by means of webs 31 integral with the extensions and with the rings. By means of the 15 rings 30, the nut 27 may be manually adjusted.

Arm section 13 and accordingly the lamp 11 may be adjusted axially of the section 10 which is advantageous especially where the 20 lamp 11 is in such a position that the arm sections 13 and 14 are disaligned. To this end, arm 10 is provided with an arcuate slot 32 in which a pin 33 is disposed and which extends removably into an aperture 32' of 25 section 13. This pin and aperture have tapering walls to prevent the pin falling into the interior of section 13. The end of the section 13 adjacent the pin 33 terminates in a lug 35 to which is fastened as by rivets 36, an expansive metallic split ring 37 which exerts a frictional pressure or has a binding 30 action with the bore wall of the section 10 and holds the arm 13 in the position to which it may be adjusted. Pin 33 prevents 35 accidental detachment of the arm sections. A suitable ornamental nut 38 may be screw threaded as at 39 to the exterior of the section 10 over the slot 32 and the pin 33 so as to prevent outward displacement of the pin.

40 In assembling the parts, the nuts 27 are adjusted so that the blocks 21 will engage the pivot portions 20 frictionally to the desired degree. Movement of the nut is imparted to the blocks since the gland extensions 26 abut the shoulders 25 of the block. The arm 10 may then be swung from the 45 portions 20 as pivots and will remain in adjusted position due to the contact of the blocks 21 with the pivots 20. In addition, 50 the lamp 11 may be moved from the pivot 15 in a plane at right angles to the general plane of movement of the arm 10. Especially when the lamp 11 is at an angle to the arm 10 it may be moved to turn the arm 55 section axially to secure further desired adjustment, of the lamp.

It might be mentioned further that in assembling the parts, element 16 is inserted through the opening of the swivel head 12 60 and the rear of arm 10 and then the pivot member 18 is inserted and soldered or fastened by means of the set screw 19. Blocks 21 are then positioned and later the pins 23 and nuts 27 are applied.

Since merely the preferred embodiment 65 has been illustrated and described, it is to be understood that changes in the details of construction may be resorted to within the spirit and scope of the appended claims.

I claim:—

1. Supporting mechanism having a swivel head, pivot means, slidable retarder means to frictionally engage the pivot means, means on the head to engage the retarder means to prevent turning movement of the 70 retarder means independently of the head relatively to the pivot means, and means movable longitudinally of the retarder and pivot means to secure the retarder means in place.

2. Supporting mechanism having a swivel head, said head having a hollow portion provided with screw threads thereat, pivot means extending into said hollow portion, said pivot means having an inclined wall, a 75 retarder member slidable on said pivot means at said wall, said retarder having a longitudinally disposed groove, means on the hollow portion extending into said groove, said retarder means having a shoulder, and 80 a nut extending into said hollow portion engaging said shoulder and provided with screw threads to engage the said screw threads of the hollow portion.

3. Supporting mechanism having a sup- 95 porting arm, a supporting head thereon, said head having portions extending at an angle to the arm and on opposite sides of the arm, said head also being cut away opposite said arm, a supporting member extending 100 into said cutaway portion, a pivot means extending from opposite sides of the supporting member, and means in said portions of the head to mount said pivot means.

4. Supporting mechanism having a sup- 105 porting arm, a supporting head thereon, said head having portions extending at an angle to the arm and on opposite sides of the arm, said head also being cut away opposite said arm, a supporting member extending 110 into said cutaway portion, a pivot means extending from opposite sides of the supporting member, means in said portions of the head to mount said pivot means, said sup- 115 porting member also having an opening, and electric conductor means extending through said opening and said arm.

5. Supporting mechanism having an arm section, a second arm section, an article supported by one of said arm sections, one of 120 said arm sections having an elongated slot, the other of said arm sections having a slot with a substantially tapered wall, a pin to fit the latter slot projecting into the first mentioned slot, one of said arm sections hav- 125 ing a lug, and a ring fastened to said lug ex- pansible to frictionally engage the other of said sections and fasten the article in ad-

justed positions through axial movement of one of the sections.

6. Supporting mechanism having an arm section, a second arm section, an article supported by one of said arm sections, one of said arm sections having an elongated slot, the other of said arm sections having a slot, a loose pin in the latter slot projecting into the first mentioned slot, and means dis-

able over said first mentioned slot and pin 10 to prevent displacement of the pin.

In testimony whereof I affix my signature in presence of two witnesses.

THOMAS B. RULE.
